DEVICE FOR COUNTING THE NUMBER OF PICKS IN A FABRIC

Arnold Eddy, Middletown, Conn., assignor, by direct and mesne assignments, of twenty per cent to E. G. Dentay, Toronto, Ontario, Canada, and fifty per cent to Michael S. Striker, New York, N. Y.

Application October 24, 1941, Serial No. 416,289

13 Claims. (Cl. 139—1)

My present invention relates to devices for counting the number of picks in a fabric as the same is being woven on a loom.

My invention has for its object a simple and efficient device for counting the number of picks per unit of length, e. g. per inch, in a fabric, the construction of the device being such that, without any calculation, it can be promptly ascertained from the reading of the instrument whether or not the fabric is being woven according to the requirements as to the number of picks per inch.

Another object of my invention consists in providing a counting and indicating device which enables direct reading of the number of picks per unit of length and which instrument can be put into operation easily by hand and automatically stops operation after counting the number of picks in the required way.

Still another object of my present invention consists of a pick-counting device which can be permanently mounted on a loom and put into operation at any time when it is desired to know whether the fabric is being woven according to the requirements.

A further object of my invention consists of a mainly mechanical counting mechanism which is of sturdy construction and adapted to operate even under the hardest working conditions.

With the above objects in view, my present invention chiefly consists of a pick-counting device which comprises in combination a part of the loom adapted to carry out the same movement each time one pick is put into the fabric, a mechanism for indicating the number of movements carried out by said loom part, a coupling means adapted to connect the loom part and the indicating mechanism, and means adapted to operate said coupling means only while the woven fabric is moving that predetermined distance in which the number of picks has to be counted.

As stated above, the operating means must be adapted to be connected by hand with the fabric while it is woven; it should be stressed that wherever in the following specification and claims this expression is used it is intended to comprehend not only constructions where the operating means are connected with the woven fabrics itself, but also constructions in which the connection is made between the operating means and any part of the loom which is moving at the same speed as the fabric. From the point of view of the present invention, direct connection between the operating means and the fabric is not of eminent importance: It is only necessary

that the operating means be connected with a moving loom part which is moving at the same speed as the fabric.

The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a plan view of a pick-counting device in accordance with my present invention, adapted to indicate the number of picks per unit of length;

Fig. 2 is a cross-section of the device shown in Fig. 1 along line 2—2;

Fig. 3 is a cross-section of the same device along line 3—3 of Fig. 1;

Fig. 4 is a plan view of the device shown in Fig. 1 during the counting operation;

Fig. 5 is another plan view of the same device after completion of the counting operation;

Fig. 6 is a plan view of a device similar to the one shown in Figs. 1 to 5, equipped with electrical coupling means;

Fig. 7 is a side view of contact means which may be used in connection with the electrical coupling means shown in Fig. 6 in inoperative position;

Fig. 8 is a plan view of the coupling means shown in Fig. 7; and

Fig. 9 is a side view of the contact means shown in Figs. 7 and 8, in operative position.

The embodiment shown in Figs. 1 to 5 comprises, as mentioned above, a part of the loom adapted to carry out the same movement each time one pick is put into the fabric woven on the loom. In this embodiment, this loom part is represented by the shaft 2 carrying out a full rotation each time one pick is put into the fabric. This shaft may be the main shaft of the loom, or another rotating loom part revolving at the same speed as the main shaft.

The pick-counting device shown in these figures comprises furthermore a mechanism 3 for indicating the number of movements carried out by this loom part, i. e., indicating the number of rotations of shaft 2, and coupling means 4 adapted to connect this loom part, i. e. shaft 2, and the indicating mechanism 3. It must be stressed that it is not essential for the shaft to perform a full rotation each time one pick is put into the fabric: It may as well carry out a part rotation while one pick is being put into

the fabric; in this case, however, the indicating device has to be built in a corresponding manner, i. e. it has to indicate during one rotation of shaft 2 the correct corresponding number of picks put into the fabric. In the same way, while the picks are being put into the fabric, this "loom part" may perform a reciprocating movement, and the indicating mechanism 3 may count the number of these movements. Thus, wherever in the following description and claims one of the expressions "part of loom" or "loom part" or "adapted to carry out the same movement each time one pick is put into the fabric woven on said loom" appear, these expressions should comprehend all embodiments enumerated above.

The device shown in Figs. 1 to 5, furthermore, comprises means adapted to operate the coupling 4 only while the woven fabric 1 is moving that predetermined distance in which the number of picks has to be counted. In the shown embodiment, these means consist of a double-armed lever 5 rotatably secured by pivot 6 to base plate 7. Lever arm 8 engages the slidable part 9 of coupling 4. Spring 10 tends to turn lever arm 8 in counter-clockwise direction about pivot 6, causing disengagement of the cooperating members of coupling 4.

The other lever arm 11 of the double-armed lever 5 is adapted to engage the timing device 12 which is regulating the time of engagement of coupling 4. This timing device consists, as shown in Figs. 2 and 3, of a longitudinal slot 13 provided in base plate 7, and of a sliding member 14 adapted to slide in slot 13. This sliding member 14 is provided with small pins 15 on its lower face facing the fabric 1; this fabric is moving in direction of arrow 16. Base plate 7 is arranged at such distance from fabric 1 that pins 15 of the sliding member 14 engage the fabric when moving in slot 13. It must be noted that the front part 17 of base plate 7 is bent upward forming thereby an upward-extending slot portion 18. When the sliding member 14 is carried by fabric 1 into this slot portion 18, its pins 15 become disengaged from the fabric 1 and the sliding member 14 ceases to move.

During its movement, the projecting portion 19 of sliding member 14 comes into contact with lever arm 11 and pushes the same in direction of arrow 20, engaging thereby coupling 4. Lever arm 11 and the projecting portion 19 are shaped in such a manner that they are in operative contact only as long as the sliding member and the fabric carrying this sliding member are moving that distance during which the number of picks has to be counted. Thus, if the projecting member 19 is provided with a sharp contacting edge, that part of lever arm 11 which is parallel to the edge of the sliding member 14 will have to be of that length for which the number of picks has to be indicated. However, it is also possible to provide lever arm 11 with an edge contacting the projecting portion 19 only at one point and to make the length of this projecting portion equal to that distance the number of picks has to be determined for. In general, the added lengths of the projecting portion 19 and of the contacting portion of lever arm 11 in direction of arrow 16, i. e. in direction of the movement of the woven fabric, must be equal to the predetermined distance for which the number of picks has to be counted. Usually, this distance will be equal to the unit of length, i. e. one inch. In this case, either the length of the contacting edge of lever

arm 11 or the length of the contacting projection 19 or their combined length has to be equal to one inch.

The counting device described above is operating in the following way: In Fig. 5, the counting device is shown in inoperative position. The counting mechanism 3 shows no indication, the clutch 4 is disengaged, and the sliding timing member 14 lies on the raised portion 17 of base plate 7 in the slot portion 18 of slot 13, disengaged from fabric 1.

For operating the counting device, the sliding member 14 is put by hand into the position shown in Fig. 1 and is pressed with pins 15 against fabric 1, engaging the same. Now, the sliding member 14 begins to move together with fabric 1 in direction of arrow 16 coming into contact with lever arm 11 and pushing the same in direction of arrow 20. Thereby the other lever arm 8 of lever 5 is turned in clockwise direction, thus engaging the cooperating members of clutch 4 and starting operation of the counting mechanism 3. This counting mechanism 3 is then operated by shaft 2 for the duration of time that the sliding member 14 is pressing the lever arm 11 in direction of arrow 20, namely for that time during which the sliding member 14 and fabric 1 are moving a predetermined distance, for instance, one unit of length.

In the moment that the projection 19 becomes disengaged from lever arm 11, spring 10 forces lever 5 to return into its position shown in Figs. 1 and 5, disengaging thereby the cooperating members of clutch 4 and stopping the movement of the indicating mechanism. Thus, after having stopped, the indicating mechanism indicates the number of rotations carried out by shaft 2 while the sliding member 14 and fabric 1 have moved a predetermined distance, for instance, one unit of length. Since the number of revolutions of shaft 2 is equal to the numbers of picks put into the fabric, the indication of indicating mechanism 3 enables direct reading of the number of picks in a predetermined length, for instance in one unit of length of the fabric 1, as the same is being woven on the loom.

The embodiment shown in Fig. 6 is very similar to the one described above: The arrangement of indicating mechanism 3, clutch 4, and rotating shaft 2 is identical. Only the operating lever and the mechanical timing mechanism are substituted by other means.

Lever 21, substituted for the operating lever 5, is turnably secured by means of pivot 22 to base plate 23. This base plate 23 is completely flat and not provided with any bent-up portion. Spring 24 forces lever 21 to turn in direction of arrow 25, disengaging the cooperating members of clutch 4. An electromagnet 26 is secured to lever 21 in such a manner that the same is forced to turn in direction of arrow 27 when the circuit 28 of this electromagnet is closed.

This circuit 28 includes besides electromagnet 26 a source of current 29 and an electrical contact arrangement 30. The contact arrangement is very similar to the timing device 12 shown in Figs. 1 to 5. The only difference is that base plate 31 is made of insulating material and provided with two contact members 32 and 33 arranged in such a manner that both of them contact the metallic sliding contact member 34 when the same is sliding in slot 13 in the way described above. The sliding contact member 34 thus serves as part of circuit 28 and closes this circuit for that time during which it moves

a predetermined distance, for instance, one unit of length. During this time interval, electromagnet 26 pulls lever 21 in direction of arrow 27, engaging thereby the cooperating members of clutch 4, and operating the indicating mechanism 3 in the same way as described above in connection with the embodiment shown in Figs. 1 to 5.

The operation of this embodiment is the same as that of the device shown in Figs. 1 to 5; the sole difference is that the electrical contact arrangement 30 used instead of the mechanical timing device 12 is connected with other parts of the counting device only by electrical conducting wires; this makes it possible to arrange the indicating mechanism 3, clutch 4, and operating lever 21 at whatever place desired, for instance, near to the main shaft of the loom, thereby avoiding the necessity of mechanical transmission from this shaft to shaft 2 of the embodiment shown in Figs. 1 to 5, which latter shaft is mechanically connected with the timing mechanism 12, and has therefore to be arranged very close above the path of the woven fabric 1.

In Figs. 7 and 8, another embodiment of an electrical contact mechanism is shown. In this embodiment the electrical circuit 28 is not closed by a sliding contact member, i. e. member 34 moved by the fabric itself, but the contact means are provided directly on the transporting roll carrying the fabric while it is woven.

It is evident that the surface of this roll is moving at the same speed as the fabric itself and, therefore, contact members arranged on the roll surface can be used for closing the electrical circuit 28 with the same result as the sliding contact member 34 carried by fabric 1.

As shown in these figures, the transporting roll 35 is provided with several contact plates 36 extending for a predetermined length, for instance, one unit of length, in direction of rotation of roll 35. The two contact members 37 and 38 of circuit 28 are insulated from each other and from the resilient plate 39 carrying the same by means of the insulating support 40. A spring-like member 41 serves for holding contact members 37 and 38 in contact with the contact plate 36 when pushed by means of push button 47 in direction of arrow 42. Pushbutton 47 and the resilient plate 39 are mounted on a stationary support 43 near to the circumferential surface of the transporting roll 35 in such a manner that the contact members 37 and 38 can be pushed into contact with one of the contact plates 36 by means of pushbutton 47.

This contact mechanism operates as follows:

The insulating support 40 and contact members 37 and 38 carried by the same are pushed by means of pushbutton 47 in direction of arrow 42 at a time when they are not just above one of the contact plates 36. As shown in Fig. 9, contact members 37 and 38 are held in this pushed-down position, adapted to slide along contact plate 36, by means of the spring-like member 41 engaging the insulating support 40 with its recessing portion 48. When the transporting roll moves in direction of arrow 44, contact plate 36 comes into contact with the pushed-down contact members 37 and 38, closing thereby the circuit 28. This circuit stays closed until the extension 45 of the spring member 41 is pushed by projection 46 of contact plate 36 in direction of arrow 44; thereby this spring-like member 41 becomes disengaged from the insulating support 75

40 and the latter together with contact members 37 and 38 is moved by the resiliency of support 39 against the direction of arrow 42 into the position shown in Figs. 7 and 8, breaking the contact between the contact members 37 and 38. Thus, the contact was closed while the transporting roll and the fabric carried by the same have moved the predetermined distance, for instance, one unit of length. During this time 10 interval, the indicating mechanism was operated by the contact mechanism in the same manner as described in connection with the embodiment shown in Fig. 6.

After resuming its initial position, the contact mechanism is ready for the next counting operation.

It will be understood that each of the elements described above, or two or more together, may also find a useful application in other types of pick counting devices differing from the types described above.

While I have illustrated and described the invention as embodied in devices for counting the number of picks, I do not intend to be limited to the details shown, since various modifications and structural changes may be made without departing in any way from the spirit of my invention. Thus, for instance, it is stated in the preceding specification and following claims that the operating means for the sliding members must be adapted to be connected by hand to the fabric. I wish to emphasize, that within the meaning of the following claims also all constructions should be comprehended in which these operating means for sliding members are not connected to the fabric itself but to a part of the loom which is moving at the same speed as the woven fabric.

It should, furthermore, be mentioned that I have shown only sliding members provided with pins for connecting these sliding members to the fabric or a loom part moving at the same speed as this fabric; however, in the same way, I also may use means for connecting the sliding members to the fabric. Thus, for instance, the contacting faces of the sliding members may be made adhesive or they may be provided with magnetic means in order to keep the sliding member in contact with a part of the loom moving at the same speed as the woven fabric.

Without further analysis, the foregoing will so fully reveal the gist of my invention that others can by applying current knowledge readily adapt it for various applications without omitting features that, from the standpoint of prior art, fairly constitute essential characteristics of the generic aspects of this invention and, therefore, such adaptations should and are intended to be comprehended within the meaning and range of equivalence of the following claims.

What I claim as new and desire to secure by Letters Patent is:

1. Device for counting and registering the number of picks in a certain predetermined length of fabric as this fabric is being woven on a loom, comprising in combination a part of said loom performing an identical movement during weaving of each filling pick, a counting and registering mechanism constructed to count and register the number of said movements performed by said loom part, and a cloth measuring mechanism constructed and arranged so as to connect said loom part with said counting and registering mechanism when required and to disconnect them automatically at the moment

when said fabric has moved from the moment of connecting said loom part with said counting and registering mechanism a distance equal to said predetermined length of fabric in which the number of picks has to be counted.

2. Device for counting and registering the number of picks in a certain predetermined length of fabric as this fabric is being woven on a loom, comprising in combination a rotating shaft carrying out one revolution during weaving of each filling pick, a counting and registering mechanism constructed to count and register the number of said revolutions of said shaft and a cloth measuring mechanism constructed and arranged so as to connect said shaft with said counting and registering mechanism when required and to disconnect them automatically at the moment when said fabric has moved from the moment of connecting said shaft with said counting and registering mechanism a distance equal to said predetermined length of fabric in which the number of picks has to be counted.

3. Device for counting and registering the number of picks in a certain predetermined length of fabric as the same is being woven on a loom, comprising in combination a part of said loom constructed to perform an identical movement during weaving of each filling pick, a counting and registering mechanism constructed to count and register the number of said movements performed by said loom part, a clutch mechanism constructed to temporarily connect said loom part and said counting and registering mechanism, and a cloth measuring mechanism constructed and arranged so as to engage said clutch mechanism when required and to disengage the same at the moment when said fabric has moved from the moment of engaging said clutch mechanism a distance equal to said predetermined length of fabric in which the number of picks has to be counted.

4. Device for counting and registering the number of picks in a certain predetermined length of fabric as the same is being woven on a loom, comprising in combination a rotating shaft performing one revolution during weaving of each filling pick, a counting and registering mechanism constructed to count and register the number of said revolutions performed by said shaft, a clutch mechanism constructed to temporarily connect said shaft and said counting and registering mechanism, and a cloth measuring mechanism constructed and arranged so as to engage said clutch mechanism when required and to disengage the same at the moment when said fabric has moved from the moment of engaging said clutch mechanism a distance equal to said predetermined length of fabric in which the number of picks has to be counted.

5. Device for counting and registering the number of picks in a certain predetermined length of fabric as this fabric is being woven on a loom, comprising in combination a rotating shaft performing one revolution during weaving of each filling pick, a counting and registering mechanism constructed to count and register the number of said revolutions of said shaft, a loom part moving at the same speed as the woven fabric, and a cloth measuring mechanism constructed and arranged so as to connect said rotating shaft with said counting and registering mechanism when required and to disconnect them automatically at the moment when said loom part has moved from the moment of connecting said rotating shaft with said counting

and registering mechanism a distance equal to that length of fabric in which the number of picks has to be counted.

6. Device for counting and registering the number of picks in a certain predetermined length of fabric as this fabric is being woven on a loom, comprising in combination a part of said loom performing an identical movement during weaving of each filling pick, a counting and registering mechanism constructed to count and to register the number of said movements performed by said loom part, a rotating transporting roll for the woven fabric, and a cloth measuring mechanism actuated by said transporting roll and constructed and arranged so as to connect said loom part with said counting and registering mechanism when required and to disconnect them automatically at the moment when a surface point of said transporting roll has moved from the moment of connecting said loom part with said counting and registering mechanism a distance equal to that length of fabric in which the number of picks has to be counted.

7. Device for counting and registering the number of picks in a certain predetermined length of fabric as the same is being woven on a loom, comprising in combination a part of said loom performing an identical movement during weaving of each filling pick, a counting and registering mechanism constructed to count and register the number of said movements performed by said loom part, a clutch mechanism temporarily connecting said loom part and said counting and registering mechanism, a rotatable transporting roll for said woven fabric, and cloth measuring means actuated by said rotatable transporting roll and constructed and arranged so as to engage said clutch mechanism when required and to disengage the same at the moment when a point of the surface of said rotatable transporting roll has moved from the moment of engaging said clutch mechanism a distance equal to that length of fabric in which the number of picks has to be counted.

8. Device for counting and registering the number of picks in a certain predetermined length of fabric as the same is being woven on a loom, comprising in combination a rotating shaft performing one revolution during weaving of each filling pick, a counting and registering mechanism counting and registering the number of said revolutions performed by said shaft, a clutch mechanism temporarily connecting said shaft and said counting and registering mechanism, and cloth measuring means actuated by the woven fabric itself and constructed and arranged so as to engage said clutch mechanism when required and to disengage the same at the moment when said fabric has moved from the moment of engaging said clutch mechanism a distance equal to said predetermined length of fabric in which the number of picks has to be counted.

9. Device for counting and registering the number of picks in a certain predetermined length of fabric as the same is being woven on a loom, comprising in combination a part of said loom performing an identical movement during weaving of each filling pick, a counting and registering mechanism constructed to count and register the number of said movements performed by said loom part, a clutch mechanism temporarily connecting said loom part and said counting and registering mechanism, a spring member tending to keep said clutch disengaged,

an electromagnet engaging said clutch when energized, and cloth measuring means constructed and arranged so as to energize said electromagnet when required and to keep the same energized until said fabric has moved from the moment of energizing said electromagnet a distance equal to that predetermined length of fabric in which the number of picks has to be counted.

10. Device for counting and registering the number of picks in a certain predetermined length of fabric as the same is being woven on a loom, comprising in combination a part of said loom constructed to perform an identical movement during weaving of each filling pick, a counting and registering mechanism constructed to count and register the number of said movements performed by said loom part, a clutch mechanism constructed to temporarily connect said loom part and said counting mechanism, a spring member tending to keep said clutch disengaged, an electromagnet constructed to engage said clutch when energized, an electrical circuit including said electromagnet, a source of current in said electrical circuit, and cloth measuring means constructed and arranged so as to close said circuit when required and to open said circuit automatically at the moment when said fabric has moved from the moment of said closing of said circuit a distance equal to that length of fabric in which the number of picks has to be counted.

11. Device for counting and registering the number of picks in a certain predetermined length of fabric as the same is being woven on a loom, comprising in combination a part of said loom constructed to perform an identical movement during weaving of each filling pick, a counting and registering mechanism constructed to count and register the number of said movements performed by said loom part, a clutch mechanism constructed to temporarily connect said loom part and said counting and registering mechanism, a lever arrangement constructed to engage and disengage said clutch mechanism, a spring member tending to hold said lever in a position in which said clutch is disengaged, and a sliding cloth measuring member constructed and arranged so as to be attached to the moving woven fabric when required, to engage and hold said lever in a position engaging said clutch mechanism, and to disengage said lever automatically when said fabric has moved from the moment of said engaging of said lever a distance equal to that length of fabric in which the number of picks has to be counted.

12. Device for counting and registering the

number of picks in a certain predetermined length of fabric as the same is being woven on a loom, comprising in combination a part of said loom constructed to perform an identical movement during weaving of each filling pick, a counting and registering mechanism constructed to count and register the number of said movements performed by said loom part, a clutch mechanism constructed to temporarily connect said loom part and said counting and registering mechanism, a spring member tending to hold said clutch mechanism in disengaged position, a lever arrangement constructed to engage said clutch mechanism, a plate-shaped support arranged near the surface of said woven fabric, and a sliding cloth measuring member constructed and arranged so as to be attached by hand to the moving woven fabric, to slide along said support engaging and holding during said sliding said lever in a position engaging said clutch mechanism and to disengage said lever automatically when said fabric has moved from the moment of said engaging of said lever a distance equal to that length of fabric in which the number of picks has to be counted.

13. Device for counting and registering the number of picks in a certain predetermined length of fabric as the same is being woven on a loom, comprising in combination a part of said loom constructed to perform an identical movement during weaving of each filling pick, a counting and registering mechanism constructed to count and register the number of said movements performed by said loom part, a clutch mechanism constructed to temporarily connect said loom part and said counting and registering mechanism, a spring member tending to keep said clutch disengaged, an electromagnet constructed to engage said clutch when energized, an electrical circuit including said electromagnet, a source of current in said electrical circuit, a plate shaped stationary support arranged near the surface of the woven fabric, one pair of stationary contact members arranged on said support and forming one point of interruption of said electrical circuit, and a sliding cloth measuring contact member constructed and arranged so as to be attached by hand to the moving woven fabric and to slide along said support in such a manner as to connect said stationary contact members when required and to automatically disconnect them after having slid on said support a distance equal to that length of fabric in which the number of picks has to be counted.

ARNOLD EDDY.
